UNITED STATES PATENT OFFICE

LEFFMAN H. LEE, OF BELLEVUE, PENNSYLVANIA, ASSIGNOR OF ONE-SIXTH TO WILLIAM B. WHARTON AND ONE-SIXTH TO JAMES M. GUTHRIE, BOTH OF PITTSBURGH, PENNSYLVANIA

FASTENING DEVICE

Application filed May 6, 1930. Serial No. 450,144.

This invention relates to steel frame buildings: buildings, that is to say, which have their frame structures erected of fabricated steel beams, joists, etc. In the construction 5 of such buildings wooden ground strips are secured to the steel frame members, and to the ground strips, base-boards or other finishing materials are attached. Plaster boards or other types of wall-forming material are either directly secured to the steel 10 frame members, or to the ground boards which have been first attached to the steel frame members. It is unnecessary to recite the many fixtures and structural parts of the 15 building which must be secured to the structural steel, suffice it to say that before my invention no adequate device was known which would permit the expeditious nailing or screwing of structural material or fixtures 20 immediately to steel frame members. The fabricated steel members now commonly used are provided with perforations for the convenient insertion of one or another of the old, unsatisfactory clamps or clips which 25 were employed as means for fastening construction material to the steel parts, and herein I shall describe a novel cup member which is adapted to be installed in one of these perforations, and when so installed to 30 receive and secure within the steel members a plug of nailable material,—thereupon affording means which permit the quick fastening of fixtures directly to the steel, either with screws or driven nails.

35 My present invention is directed to the structure of the plug-receiving member or cup, and concerns especially a plug-receiving member which is so particularly formed as to provide efficient means for preventing its withdrawal, once it has been installed in 40 one of the perforations of a steel frame member. In Fig. I of the accompanying drawing is shown fragmentarily an elevation of a typical structural steel frame member, and in 45 one of the perforations thereof there appears in top elevation the device of my invention. Fig. II is an end view of the steel frame member, showing in side elevation the plug-securing member. Fig. III is a view in longitudinal section, and to larger scale, through the

55 plug-securing member, illustrating it inserted in a steel frame member, with a nailable plug ready to be driven into its final position in the plug-securing member. Fig. IV is a sectional view, similar to Fig. III, showing the plug and plug-receiving member in assembly for service, i. e. ready to receive a screw or driven nail. And Fig. V is a view in side elevation of a plug of slightly modified structure.

60 In general the device of my invention comprises a metallic member which is adapted to be inserted in one of the usual orifices with which steel frame members (as mentioned above) are provided, and to receive and secure permanently a plug of nailable material in such orifice. In the drawing the reference numeral 1 is applied to a typical form of steel frame member—a structural angle, 65 and in one of the orifices 2 a plug-receiving 70 member 3 is installed. The member 3 is adapted to secure in the orifice 2 through which it extends a core or plug 4 of nailable material, such, for example, as wood, hemp, or any material or composition which has capacity of holding a screw or driven nail.

75 As appears to larger scale in Fig. III the plug-receiving member 3 is formed with means for limiting the extent of its insertion in the orifice 2; such means comprising, conveniently, the flange 5 which abuts or overlies the outer periphery 2a of the orifice. In the wall of the plug-receiving member an indentation is impressed (such indentation 80 advantageously is in the form of an annular 85 groove 6) which, as will presently appear, is a feature of my invention. The material of which the plug-receiving member is formed is desirably a metal having some degree of ductility, such a metal as soft steel, 90 brass, copper, or lead alloy, etc.—a metal which may be displaced or shifted from the groove 6 to form a latching shoulder beneath the lower periphery 2b of the orifice. That is to say, the material of which the member 95 is formed should be, and in fact is, such that, upon driving the plug 4 from its position in Fig. III into its permanent location within said member (Fig. IV), the metal which forms the wall of the indentation 6 may move 100

downwardly and outwardly, to form a latching shoulder 7. Manifestly, such latching provides a positive locking of the member 3 in the angle 1. By forming the member 3 of a somewhat ductile metal, the portion of the member 3 which remains within the orifice 2 expands (upon the powerful insertion of the plug 4) into tight engagement with the wall of the orifice, and such expansion in itself has been found to be a desirable characteristic of my device. In fact, to enhance this expansion, I contemplate slitting the flange and wall of the member, as indicated at 8. When the cup is so slit, of course, the ductility of the material of which the plug-receiving member is formed need not be as great as it would otherwise have to be.

With the device so assembled (Fig. IV) in the steel member 1 it is possible to nail or screw ground-boards, or other structural fixtures immediately to the steel, the nailable plug 4 readily receiving and holding the driven nail or screw.

The modified plug-securing member 3a (Fig. V) is provided with a plurality of grooves or serrations 9, which grooves, although I now believe are not as effective as the structure above described, are to be considered within the scope of my invention.

Knurling the wall of the plug-receiving member beneath its flange 5 may also be found to give a certain degree of success in the matter of locking the member in an orifice.

Notice is hereby given of my co-pending applications Serial No. 446,419, filed April 22nd, 1930, Serial No. 466,378, filed July 8th, 1930, and Serial No. 477,810, filed August 26th, 1930.

I claim as my invention:

1. In a device to permit the nailing or screwing of construction material to a steel frame member which is provided with an orifice, the combination of a plug-receiving member adapted to be inserted in said orifice, a nailable plug adapted to be permanently inserted in said plug-receiving member, said plug-receiving member being formed with an indentation in its wall which is adapted upon the insertion of the plug to cause the wall of said member to bulge outward over the peripheral edge of said orifice.

2. The structure of the next preceding claim in which said indentation comprises an annular groove.

3. In a device to permit the nailing or screwing of construction material to a steel frame member which is provided with an orifice, the combination of a plug-receiving member adapted to be inserted in said orifice and provided with means for limiting the extent of such insertion, a nailable plug adapted to be permanently inserted in said plug-receiving member, said plug-receiving member including means for limiting the extent of the insertion of said nailable plug there-

into, and an indentation in the wall of said last-mentioned member which is adapted upon the insertion of said plug to cause the wall of said member to bulge outward over the peripheral edge of said orifice.

4. In a device to permit the nailing or screwing of construction material to a steel frame member which is provided with an orifice, the combination of a plug-receiving member adapted to be inserted in said orifice and provided at one terminal with means which upon the insertion of the plug-receiving member of said orifice, abuts the outer peripheral edge of said orifice, said plug-receiving member having capacity of expansibility in at least so much of its extent as lies within said orifice, and a nailable plug adapted to be permanently inserted in said plug-receiving member, means included in the last-mentioned member for limiting the extent of such insertion of said nailable plug, and an indentation in the wall of said plug-receiving member which is adapted upon the insertion of said plug to cause the wall of said member to bulge outward over the peripheral edge of said orifice.

In testimony whereof I have hereunto set my hand.

LEFFMAN H. LEE.
